EX

D9532

OR D 7,792

UNITED STATES PATENT OFFICE.

CHARLES W. HILL, OF DERBY, CONNECTICUT.

DESIGN FOR TABLE-CUTLERY.

Specification forming part of Design No. 7,792, dated October 13, 1874; application filed August 19, 1874.
[Term of Patent 3½ years.]

To all whom it may concern:

Be it known that I, CHARLES W. HILL, of Derby, Connecticut, have invented a Design for Table-Cutlery Ornamentation, of which the following is a specification:

This design is especially adapted for pie, cake, butter, and fish knives, the blades of which are stamped with ornamental work by steel dies.

In the accompanying photographic illustration I admit the main ornamentation to be bold, but the remaining ornamentation and bordering are not; but as the accompanying illustration so fully represents the said design I do not consider any further explanation necessary to enable any one skilled in the art to repeat it for practical purposes, and will simply state that—

I claim as my design for the ornamentation of table-cutlery, such as fruit, cake, and pie knives and analogous articles—

1. The pendent flower and leaves branching out from the bordering, substantially as shown.

2. The upright flower within the inclosure formed at the lower point of the border proper by the elision border, all substantially as shown.

3. The border proper, with the elision borders at the apex and base, all substantially as shown.

CHARLES W. HILL.
